(57) **CLAIM**

The ornamental design for a wound dressing, as shown and described.

DESCRIPTION

FIG. 1 is a perspective view of a wound dressing illustrating a superstrate opposite an adhesive layer that is covered by a release liner, with the superstrate having a compressed ring surrounding an elevated portion according to one embodiment;

FIG. 2 is a top side view thereof;

FIG. 3 is a bottom side view thereof;

FIG. 4 is a right side view thereof, where a left side view is not presented as it is a mirror image of the right side view;

FIG. 5 is a front side view thereof, where a back side view is not presented as it is a mirror image of the front side view;

FIG. 6 is a cross-sectional view taken laterally through the wound dressing and viewed from the front side to illustrate the compressed ring surrounding the elevated portion; and,

FIG. 7 is a partial cross-sectional view of the wound dressing.

In FIG. 1 and FIGS. 3-5 the broken lines illustrating the release liner of the wound dressing are for illustrative purposes only and form no part of the claimed design. The release liner is removed in the view of FIG. 6.
